UNITED STATES PATENT OFFICE

GEORGE HERBSTER, OF CLEVELAND, OHIO, ASSIGNOR TO THE BAUER IGNITION COMPANY, OF CLEVELAND, OHIO, A CORPORATION OF OHIO

ELECTRICAL CONNECTER

Application filed July 18, 1929. Serial No. 379,120.

My invention is an improvement in terminal connecters for electrical conductors and relates more specifically to a detachable connector for electrically connecting a conductor and terminal post.

Heretofore connections between conductors or wires and terminal posts have been made by looping the wire end about the post and securing the wire in place by means of a nut. Connections are also made by passing the wire through an opening in the post and securing it by set screw operating on the post. The more usual form of connections, however, is the use of a flat metal strip or lug secured to the end of the wire and provided with an opening or slot which engages the post. This lug or strip in turn is secured in close contact with the post, or a shoulder of the post, by the use of a threaded nut which screws onto the post.

All such connecters however have a tendency to become loose or disengaged, due to vibration of the apparatus on which they are used, or to a strain on the wire. Furthermore, more time is consumed in making such connections, and generally two hands and tools are required to make such connections with any degree of security. Another defect of such connections is that the rigidity with which they are formed by the devices mentioned, subjects the wire itself to bending stresses, which cause it to deteriorate or break with the consequent danger arising from severed connections.

One object of my invention is to provide a simple and easily constructed device which will make such a connection, without the use of tools or loss of time, yet will remain secure under adverse conditions.

Another object is to provide a device which can be used on plain, threaded or grooved posts and which will provide a large area in contact with the post.

A further object is to provide an attachment that cannot be pulled off from the post unless by force so great as to break the conductor itself, and one which is bound to the wire so that it is practically an integral part thereof.

Another object of my invention is to make

a secure and firm but resilient connection which will permit relative rotary movement of the connector about the post without loosening the connection, and which will also relieve strains on the conductor.

Other purposes and advantages of my invention will become apparent from the following description of several embodiments thereof, in which reference is made to the accompanying drawings by the use of numerals, the same numerals representing the same parts in the various views.

In the drawings—

Fig. 1 is a plan view of one form of my invention showing the connector engaging the terminal post.

Fig. 2 is a similar plan showing the connector disengaged and ready for removal.

Fig. 3 is an end elevation of the connector shown in Figs. 1 and 2.

Fig. 4 is a side elevation of the connector partly in section shown in Figs. 1 and 2.

Fig. 5 is a plan view of another form of my invention.

Fig. 6 is a plan view of still another form of my invention, and

Fig. 7 is a side elevation partly in section of the form of my invention shown in Fig. 6.

Referring now to Figs. 1 to 4 inclusive, a terminal post 1 is shown provided with horizontal grooves. A head comprising a pair of cooperating contact jaws 2 and 3 is provided with an opening 4 preferably located so that its central axis lies in the line of division of the adjacent surfaces 5 and 5a of the contact jaws 2 and 3 when the same are in contact. Means are provided to close the jaws 2 and 3 about the post 1, and in the present embodiment comprises split ring springs 6 and 7 seated in the grooves 8 formed in the outer surface of the respective jaws 2 and 3. The jaws 2 and 3 are provided with arms 9 and 10 respectively preferably formed integral with the jaws 2 and 3. These arms are pivotally connected as at 11. One of the arms designated 10 is flattened toward the end so as to form flanges 12 and 13, which may be clamped about the conductor 14 to secure it to the arm 10.

Electrical contact between the conductor

and arm is attained, as is also greater security, by means of the openings 15 and 16 in arm 10, through which the wire is passed and bent back and soldered. The arms 9 and 10 are formed so that, as they are pressed together, they will force the jaws 2 and 3 apart, but will themselves come into contact before the faces 5 and 5a of the contact jaws are spread sufficiently far apart to permit them to be moved radially from the post. This prevents further spreading of the jaws, yet allows the jaws 2 and 3 to move relatively apart a sufficient distance to enlarge the smallest diameter of the opening 4 to a size 15 slightly greater than the largest diameter of the post 1, so that the head may be lifted axially from the post.

It should be understood that posts of various cross section can be used and the shape 20 of the opening 4 varied to correspond with the same. Cross sectional shapes of the posts and the forms of my invention here shown are used only for the purposes of illustration.

By fastening the wire to the arms 9 or 10 25 at a point somewhat removed from the post 1 an axial lift on the contact jaws 2 and 3 is prevented when a pull is applied on a wire parallel to the post 1.

The resiliency of the arms 9 and 10 and the 30 binding springs 7 and 8 tend to relieve a sudden jerk on the wire, which might otherwise cause it to snap or break. The fact that the connection is free to turn peripherally about the post and yet maintain a firm contact over a large area prevents weakening of the wire, due to doubling back and kinking.

The faces 5 and 5a of the jaws 2 and 3 may 40 be formed so that portions of the opening 4 contact with the post and grip it firmly while the faces 5 and 5a remain very slightly separated.

Fig. 5 shows another form of my invention in which the arms 17 and 18 are formed with 45 inwardly extending rockers 19 and 20 to provide a fulcrum for the jaws 21 and 22. It will be noted that by means of the rockers 19 and 20 the fulcrum point is variable in a line radial to the post 1. Contact of the arms at 23 limits the extent to which the contact 50 jaws 21 and 22 can be separated. In this embodiment of my invention the springs 24 and 25, similar to springs 7 and 8 in Figs. 1 to 4, normally hold the jaws together to form the head, and to clamp the jaws to the post. 55 The wire is secured to one of these arms, shown as arm 18, in the same manner as wire 14 is secured to the arm 10 in the form shown in Figs. 1 to 4.

Fig. 6 shows an arrangement of the jaws 60 26 and 27 in which the springs 28 and 29 perform the same functions as the springs 24 and 25 in the embodiment shown in Fig. 5, and draw the jaws 26 and 27 relatively together. In this arrangement, the jaw 26 of 65 the head is provided with arms forming a

loop 30, to one end of which the wire is connected in the same manner as in the previously mentioned forms. This loop is so formed that an axial pull on the wire is radial to the post and draws the jaw 26 more tightly 70 against the post. The other jaw 27 is provided with a grip 31. To remove this connector from the post the jaw 26 is forced away from the post by pushing the loop 30 toward the post. While the jaw 26 is somewhat removed from the post 1, the grip 31 is caught between the fingers and held, so that 26 and 27 remain relatively apart, the opening 28 being enlarged sufficiently so that the head of the connector may be lifted axially 75 from the post.

It is to be understood that I do not intend to limit my invention to the forms and means shown in the drawings and the foregoing specification, but have used such only for the purpose of illustration.

I claim:

A terminal connector comprising a pair of jaws for gripping a terminal post, a finger grip on one of the jaws, an arm extending from the other jaw, said arm having a looped portion extending in the plane of the finger grip and enclosing the same, and contractible means on the jaws to normally grip the jaws about the terminal post.

In testimony whereof, I hereunto affix my signature.

GEORGE HERBSTER.
